UNITED STATES PATENT OFFICE.

JOHN W. EDMONDS, OF NEW YORK, N. Y.

TRANSPARENT BLOWER FOR FIRE-PLACES.

SPECIFICATION forming part of Letters Patent No. 280,154, dated June 26, 1883.

Application filed February 17, 1883. (No model.)

To all whom it may concern:

Be it known that I, JOHN W. EDMONDS, of the city, county, and State of New York, have invented an Improvement in the Means of Supporting a Blower on a Grate Fire-Place, of which the following is a specification.

The invention will first be described in connection with all that is necessary to a full understanding thereof, and then pointed out in the claim.

Figure 1 of the drawings is a front view of a fire-place with my invention applied thereto. Fig. 2 is a vertical cross-section; and Fig. 3, a like cross-section, showing a slight modification.

In the drawings, A represents a blower, made of glass or some transparent material, and which may be placed in a suitable frame. The blower rests against the rear surface of the side posts

of the mantel, and is held across the upper 20 part of the fire-place opening, while its lower edge is sustained in hook-clips B, fastened to the wall or the uprights of the mantel, and its upper edge in a stud or clip, C, fastened in the fire-place wall. By these means the blower 25 is always held to the fire-place loosely, so that it can readily contract and expand without danger of fracture.

What I claim as new and of my invention is—

The combination, with a grate fire-place, of the clips B C, adapted to support a blower, as shown and described.

JOHN WILLIAM EDMONDS.
